[57] CLAIM

The ornamental design for a corner cable bracket, as shown.

DESCRIPTION

FIG. 1 is a top side perspective view of my new corner cable bracket;

FIG. 2 is a top plan view;

FIG. 3 is a top rear perspective view;

FIG. 4 is a bottom plan view;

FIG. 5 is a rear elevation; and,

FIG. 6 is a front elevation.

The broken line showing the corner frame members are for illustrative purposes only and forms no part of the claimed design.

FIG. 1FIG. 2FIG. 3FIG. 4FIG. 5FIG. 6
